NECKTIE

George A. Mueller, University City, Mo.

Application December 15, 1938, Serial No. 245,903

3 Claims. (Cl. 2—146)

This invention relates generally to neckwear and, more particularly, to a certain new and useful improvement in neckties of the so-called "four-in-hand" type.

In present day neckwear of the "four-in-hand" type, repeated efforts have been made to provide a so-called resilient construction which will neither become particularly wrinkled nor distorted as a result of repeated knotting or tying. Unfortunately, so far as I am aware, any method of necktie construction which provides a sufficiently resilient structure will, at the same time, result in a necktie that does not have sufficient rigidity to retain its shape or appearance. On the other hand, the removal of wrinkles and the restoration of initial or original shape by ironing or pressing are difficult of attractive accomplishment, for ironing or pressing almost invariably alters the surface appearance of the material, and leaves prominent streaks co-incident with the seams and bulkier areas of the necktie.

My invention hence has for its primary objects the provision of a necktie which is simple in form and structure, which may be cheaply and economically constructed, which may be readily tied with the same ease and convenience of a conventional four-in-hand necktie, which is highly resistant to wrinkling and deformation, and which may be readily and conveniently pressed or ironed into original shape without altering or damaging the material of the necktie and without retailoring or reconstructing the inner structural portions of the necktie.

And with the above and other objects in view, my invention resides in the novel features of form, construction, arrangement, and combination of parts presently described and pointed out in the claims.

In the accompanying drawings (2 sheets), Figure 1 is a plan view of a necktie embodying my present invention;

Figures 2 and 3 are enlarged fragmentary views, illustrating the one end of the necktie in partially and fully opened-out positions, respectively;

Figure 4 is an enlarged transverse sectional view of the necktie, taken approximately along the line 4—4, Figure 1;

Figure 5 is a fragmentary view of a partially open end of a modified form of necktie embodying my present invention;

Figure 6 is a transverse sectional view of the modified necktie of Figure 5;

Figure 7 is a plan view of another modified form of necktie of my present invention;

Figure 8 is a plan view of the modified necktie

of Figure 7, the necktie being in partially opened-out position; and

Figure 9 is a plan view of a further modified form of necktie of my invention in fully opened-out position.

Referring now in more detail and by reference characters to the drawings, which illustrate practical embodiments of my invention, the preferred necktie A of Figure 1 is constructed of any suitable fabric, such as foulard, mogador silk, or the like, of such size, form, and contour to include, as shown, a front or face-panel 1 and having opposed side margins 2, 3.

Integrally joined to the face panel 1 along the margin 2, is a main flap 4, which normally is folded on the margin 2 to extend substantially flatwise across the rearwardly presented face of the panel 1 and terminates at its free margin 5 at a distance substantially inwardly from the opposite face panel margin 3.

Similarly integrally joined to the face panel 1 along the margin 3, is a back panel 6, which normally is folded on the margin 3 to extend flatwise inwardly from the margin 3 over the rearwardly presented face of the front panel 1 and also over the flap 4, the panel 6 terminating at its outer or free margin in a fold 7 disposed a short distance inwardly from the margin 2.

Along such outer margin or fold-line 7, the back panel 6 is integrally continued in a tuck-flap 8, which is disposed flatwise intermediate the flaps 4 and 6 and terminates along its free margin 9 in substantial overlying registration with the free margin 5 of the main flap 4, all as best seen in Figure 1 and for purposes presently more fully appearing.

As is customary in necktie construction, the tying-ends a, b, of the tie are, as shown, greatly enlarged relatively to the intermediate or so-called neck-encircling portion or band c of the neckband c, the fabric of the tie A is longitudinally permanently stitched together by a short line of stitches 10.

Stitched or otherwise secured adjacent the margin 2 upon the rearwardly presented face of the main flap 4 approximately midway between the neckband c and the larger end a of the tie A, is preferably the female or socket portion 11 of a conventional snap fastening couplet, which is adapted for retentive co-operation with the opposed male or ball portion 12 stitched or otherwise secured in registering location upon the underlying face of the tuck-flap 8, as best seen in Figure 2.

In use, the tie A is folded, shaped, and pressed,

as shown in Figure 1, and the snap fastening elements 11, 12, engaged. In this position, the tie A has the shape of a conventional four-in-hand tie and may be readily knotted and used in the ordinary manner. By reason of the peculiar shape and folding of its fabric, however, the various panels of the tie A will neither tend to buckle nor to bend apart during use. In repeated tying, the larger end a usually becomes wrinkled or misshapen. In such event, the snap fastener elements 11, 12, may be readily disengaged and the tie-end a folded open, as shown in Figure 3. In this position, the tie may be very conveniently ironed from the wrong face or side, so that the outer face or side of the material will neither be harmed nor damaged by direct contact with the iron or other pressing member, following which operation, the necktie may be conveniently restored to original shape for repetitious use.

With the panel and flap portions made and folded in the manner set forth, and with the two flap parts terminating at their free marginal edges 5 and 9 on lines somewhat spaced from the line of fold at 3, the folded up tie is of such construction that these marginal edges terminate at a distance spaced from the line of fold between the face and back panels, and consequently not more than two thicknesses of material are presented along the line of each of the folds. This construction results in economy of material and lessens possibility of the material of the flaps being wrinkled or bunched up, and at the same time leaves each of the folded portions along the lines of fold at 2 and 3 and 1 with not more than two thicknesses of material, thus tending to smooth rolling or folding and precluding possibility of bunching or twisting and wrinkling of inner portions.

The modified necktie A' of Figures 5 and 6 is substantially identical in all respects with the necktie A, except that a lining-member 13, fabricated of wool or other suitable material, is employed. The lining-member 13 includes a pair of similarly shaped panels 14, 15, integrally joined and folded into overlying registration along a common margin 16, the panel 14 being inserted between the opposed faces of the main panel 1 and the main flap 4, the panel 15 being similarly inserted between the opposed faces of the back panel 6 and the tuck-flap 8, and the margin 16 extending along the margin 3, all as best seen in Figures 5 and 6.

The modified necktie A² of Figures 7 and 8 includes a front panel 17 having opposed side margins 18, 19. Joined integrally with the front panel 17 along the margin 18, is a main flap 20, which is presented flatwise inwardly over the rearwardly presented face of the front panel 17 and terminates in a free margin 21 located substantially inwardly from the panel-margin 19. Similarly joined integrally with the face panel 17 and presented inwardly flatwise across the rearwardly presented face of the main flap 20, is a back panel 22 terminating along its outer margin 23 substantially inwardly from the front panel margin 18. Formed integrally with the back panel 22 at its margin 23 and presented flatwise inwardly over the rearwardly presented face of the main flap 20, is a tuck-flap 24 having its inner or free margin 25 spaced substantially inwardly from, and extending in substantial parallelism with, the front panel margin 19. In the region of the smaller tying-end b of the necktie A², the main flap 20 is provided along its outer margin 21 with an inwardly turned short triangular tuck-

flap 26, all as best seen in Figures 7 and 8 and for purposes presently more fully appearing.

Disposed within the folded fabric of the necktie A², is a lining member 27, which includes two identically shaped panels 28, 29, integrally joined together and folded into overlying registration along a common margin or fold line 30, the panel 28 being inserted between the opposed faces of the panel 17 and the main flap 20, and the panel 29 being inserted between the opposed faces of the rear panel 22 and the tuck-flap 24. The lining 27 is held in place by two lines of stitches 31, 32, respectively positioned slightly inwardly of, and extending parallel with, the main flap margin 21 and the tuck-flap margin 25. The opposed faces of the main flap 20 and the tuck-flap 24 are provided with a plurality of co-operable snap fastener elements 33, 34, for securing the fabric of the necktie in properly folded position.

After the necktie A² has been worn several times, the snap elements 33, 34, may be disconnected and the fabric unfolded, in which position the tie may be readily and conveniently ironed and then again restored to original condition.

The modified necktie A³ is substantially identical in all respects to the necktie A², except that a lining, such as the lining 27, is entirely omitted, the necktie A³ being similarly readily opened out for ironing and equally conveniently restored to normal condition for wear.

Thus I provide a necktie which fulfills in every respect the objects stated, and it should be understood that other changes and modifications in the form, construction, arrangement, and combination of the several parts of the necktie may be made and substituted for those herein shown and described without departing from the nature and principle of my invention.

Having thus described my invention, what I claim and desire to secure by Letters Patent is,

1. A four-in-hand necktie comprising a body portion shaped and folded to present a face panel having a main back flap at one side folded rearwardly and inwardly and having a back panel at the other side folded rearwardly and inwardly to overlie the back flap, said back panel being provided at its outer edge with a tuck flap infolded to lie between the back panel and the main flap, said flaps terminating at their free marginal edges at a distance spaced from the line of fold between the face and back panels whereby not more than two thicknesses of material are presented along the line of each of the folds and said flaps in the knot forming and tying end being unsecured to the panels except at the folded edges thereby permitting complete unfolding and flat opening out of said panels and flaps of the larger tying end, and a two-part fastener having one part thereof secured on the tuck flap only and located inwardly from the infolded edge and having the other part secured on the back flap only whereby when the fastener is closed the fastener and the securement therefor are covered and concealed by the back panel and the knot forming and larger end portion of the tie.

2. A four-in-hand necktie comprising a body portion shaped and folded to present a face panel having a main back flap at one side folded rearwardly and inwardly and having a back panel at the other side folded rearwardly and inwardly to overlie the back flap, said back panel being provided at its outer edge with a tuck flap in-

folded to lie between the back panel and the main flap, said flaps terminating at their free marginal edges at a distance spaced from the line of fold between the face and back panels 5 whereby not more than two thicknesses of material are presented along the line of each of the folds and said flaps in the knot forming and tying end being unsecured to the panels except at the folded edges thereby permitting complete unfolding and flat opening out of said panels and flaps of the larger tying end, a two-part fastener having one part thereof secured on the tuck flap only and located inwardly from the infolded edge and having the other part secured on the back 10 flap only whereby when the fastener is closed the fastener and the securement therefor are covered and concealed by the back panel and the knot forming and larger end portion of the tie is loosely rolled and unsecured at the folds and presents not more than two thicknesses of material 15 along the line of each of the folds thereof, said panels and flaps being similarly folded in the neck band portion, and separable fastener means holding the neck band portion folded. 20

25 3. A four-in-hand necktie comprising a body portion shaped and folded to present a face panel having a main back flap at one side folded rearwardly and inwardly and having a back panel at the other side folded rearwardly and inwardly to overlie the back flap, said back panel being provided at its outer edge with a tuck flap infolded to lie between the back panel and the main flap, said flaps terminating at their free marginal edges at a distance spaced from the line of fold between the face and back panels whereby not more than two thicknesses of material are presented along the line of each of the folds and said flaps in the knot forming and tying end being unsecured to the panels except at the folded edges thereby permitting complete unfolding and flat opening out of said panels and flaps of the larger tying end, and a two-part fastener having one part thereof secured on the tuck flap only and located inwardly from the infolded edge and having the other part secured on the back flap only whereby when the fastener is closed the fastener and the securement therefor are covered and concealed by the back panel and the knot forming and larger end portion of the tie is loosely rolled and unsecured at the folds and presents not more than two thicknesses of material along the line of each of the folds thereof, and said panels and flaps being similarly folded and being secured in folded relation in the neck band portion. 25
